MARK BELCHER, Inventor

By Jesse R. Stone

his Attorney

UNITED STATES PATENT OFFICE.

MARK BELCHER, OF WEST COLUMBIA, TEXAS, ASSIGNOR OF ONE-THIRD TO G. H. DAVIS, OF WEST COLUMBIA, TEXAS.

OIL-TREATING MIXER.

1,417,965.

Specification of Letters Patent. Patented May 30, 1922.

Application filed December 27, 1921. Serial No. 524,932.

To all whom it may concern:

Be it known that I, MARK BELCHER, a citizen of the United States, residing at West Columbia, Brazoria County, Texas, have invented a certain new and useful Improvement in Oil-Treating Mixers, of which the following is a full, clear, and exact description, such as will enable others skilled in the art to which it appertains to make and use the same.

My invention relates to liquid mixers particularly adapted for the mixing of different grades of oil or the mixing with crude oil of ingredients designed to clear or purify it of foreign constituents such as basic sediment, water, etc.

In the apparatus now commonly used for mixing such liquids, long strings of pipe are employed and the oil and purifying ingredients are forced by pump pressure through the long passage thus provided in such manner that an intimate mixture will finally result. This method necessitates a large amount of pipe and a place to lay the pipe. Furthermore the oil, which is commonly heated, is cooled greatly in its passage through the pipe.

An object of my invention is to provide a mixer which will thoroughly mix the oil with the other liquids in a comparatively small space, thus necessitating only a small installation.

Another object is to provide a mixer which is simple and strong in construction and economical to use. Other objects and advantages will be apparent to one skilled in the art after the device is more clearly understood.

Referring to the drawings herewith wherein like numerals of reference are applied to like parts in all the views: Fig. 1 is a central longitudinal section through a length of pipe, my mixing apparatus therein being partly in elevation. Fig. 2 is a transverse section on line 2—2 of Fig. 1. Figure 3 is a broken section on line 3—3 of Fig. 2.

In designing my improved mixer I have contemplated using an ordinary length of pipe 1. This pipe is threaded at 2 at both ends thereof for coupling of the same within an ordinary string of pipe. It is also threaded internally at 3, at each end to accommodate a bearing plug 4, adapted to be

screwed within the threaded portion. Each 55 of these bearing plugs is of similar construction, and one only need be described. It comprises a solid block of metal having a central cylindrical opening 5 therein to support the agitating member. On the inner 60 face of the bearing member the opening 5 is counter-bored and enlarged at 6 to provide a seat for a ball-race 7 or similar non-friction device to facilitate rotation of the 65 agitating member. The ball-race 7 is protected on its inner side by a threaded washer 8 fitted about the shaft of the mixing member.

To provide a passage for fluid through my mixing device the bearing plugs 4 are 70 perforated by a plurality of openings 9. These openings are directed in a somewhat spiral direction at an angle inclined to the central axis of the pipe 1. This angle is so arranged as to direct the fluid in the proper 75 direction against the mixing device. These openings may be of any number or size sufficient to permit the flow of the required amount of liquid through the mixer.

The mixing member comprises a longitudinal shaft having agitating blades 10 at each end thereof. These blades are intended to cause a rotating motion of the fluid and of the agitating means. They may be of any ordinary form, and I have shown 80 in the drawing one spirally arranged blade at each end of the mixing member. It will be noted that both of these blades have the same formation so that the passage of the 85 fluid will cause a rotative effect in the same 90 direction at each end of the mixer.

Between the two blades 10, I contemplate providing a further device for more thoroughly beating up and mixing the liquid flowing through the device. For this purpose I have formed a central cylindrical shaft 11, having keyed thereto at 12 a sleeve, 95 13. This sleeve has thereon a series of radially extending bristles 14 forming a brush. As will be apparent, these bristles 100 will be caused to rotate with the blades 10 and thereby assist in thoroughly mixing and agitating the fluid.

In the operation of my device the oil to be treated will be pumped from the pit 105 through the pipe 1 which houses my agitator, to the settling tank where the ingredients of the oil are adapted to separate. As the

oil, with the ingredients mingled therein, are forced by the pumps through my agitator, the flow is given a whirling motion by the direction of the passages 9 in the bearing plugs. This whirling is in the proper direction to impart a rotative movement to the blades 10. The flow of the fluid along the said blades will further carry out this rotative movement and will cause the mixer 10 to revolve rapidly. As the fluid passes along the blades and past the agitating brush 14, the ingredients will be thoroughly and intimately mixed. This mixture will be facilitated by the passage of the fluid 15 through the small openings 9 in the plugs. Therefore, when the fluid issues from the agitator the different ingredients will be ready for discharging into the separating or settling tank.

20 The advantages of this type of construction over the usual pipeline mixer will be apparent to one skilled in the art, without further description.

What I claim is new and desire to protect by Letters Patent is:

25 1. In a device of the character described, a length of pipe, a bearing member in each end thereof, a mixing member in said pipe, having its ends journalled in said bearing members, spirally arranged agitating blades 30 on said mixing member, and a brush intermediate the ends thereof, said bearing mem-

bers having constricted passages there-through.

2. In a device of the character described, 35 a tubular chamber, a bearing member in each end thereof, a mixing member journalled in said bearing members, agitating blades on said mixing member, and a brush on said mixing member, said bearing member having constricted passages there-through adapted to direct fluid against said blades at an angle to the axis of said chamber.

3. In a device of the character described, 45 a tubular chamber, a rotatable mixing member journalled for rotation therein, spirally arranged agitating blades on said member, and agitating brushes between said blades, said mixing member being adapted for rotation by the passage of fluid through said chamber.

4. In a device of the character described, 55 a tubular chamber, a mixing member, perforated bearing plugs at each end of said chamber for said member, a spirally arranged blade at each end of said member and a brush on said member between said blades.

In testimony whereof, I hereunto affix my 60 signature, this the 19 day of December, A. D. 1921.

MARK BELCHER.
